FIG. 4.

FIG. 5.

INVENTOR.
LAURENCE E. FRENCH.
BY Chas. E. Townsend

ATTORNEY

UNITED STATES PATENT OFFICE.

LAURENCE E. FRENCH, OF SEBASTOPOL, CALIFORNIA.

OIL BURNER.

Application filed November 3, 1920. Serial No. 421,437.

To all whom it may concern:

Be it known that LAURENCE E. FRENCH, a citizen of the United States, residing at Sebastopol, in the county of Sonoma and 5 State of California, has invented new and useful Improvements in Oil Burners, of which the following is a specification.

This invention relates to a fuel burner and particularly pertains to a rotary burner for 10 use with liquid fuel. It is the principal object of the present invention to provide a rotary burner for liquid fuel which is so constructed as to insure that the fuel will be thoroughly atomized as it is delivered to 15 a combustion chamber, and that the mechanical means for agitating and delivering the fuel to the fuel jet and throwing it therefrom will be simple in construction and arrangement so that a blaze of maximum 20 intensity may be obtained in a limited zone, the invention being so constructed as to permit burner structures of various capacity to be readily made from multiple units and assembled in such a compact manner as to 25 allow the burner to be carried from place to place.

The present invention contemplates the use of a rotary nozzle from which oil vapor is thrown, and which nozzle is disposed in 30 the path of travel of a current of air in a manner to arrest the centrifugal action of the oil and carry it forwardly of the jet in a manner to produce a concentrated blaze, the supply of air being produced by multiple 35 rotary fans which are driven in synchronism with the rotary movement of the nozzle, and which insure that a desirable relation will exist between the velocity of the air flowing around the nozzle and the 40 velocity of the fuel vapor being thrown off from the nozzle by centrifugal force, said fans and nozzle being driven from a single motor while all of the unit may be positioned upon a movable tripod.

45 The invention is illustrated by way of example in the accompanying drawings in which—

Figure 1 is a view in central vertical section through the burner showing the correlation 50 of its parts, and further disclosing it with parts broken away for the sake of convenience.

Fig. 2 is a view in longitudinal section through the burner nozzle.

55 Fig. 3 is a view in longitudinal section through another form of a burner nozzle.

Fig. 4 is a view in section and elevation showing the end of a fan blower with its cap removed and with one of its walls broken away to more clearly disclose the fan 60 blades.

Fig. 5 is a view in elevation illustrating the application of the invention.

Referring more particularly to the drawing, 10 indicates a tripod upon which is 65 mounted a bolting plate 11. This plate is disposed upon the top of the tripod and is secured by a center bolt 12, which extends through opening 13 in the plate. On one end of the plate 11, a motor 14 is mounted, 70 while on the other end a fan and burner structure 15 is secured. The plate is formed by the vertical flange 16, to which a gear housing 17 will be secured. This housing is clearly shown in Fig. 4, where it will be 75 seen to have a large circular body portion with a lower semicircular extension thereof for the reception of a spur gear 18 forming part of the gear train which will be hereinafter described. A cover plate 19 is provided for the housing and interposed between it and the bolting flange 16 of the base plate 11. Suitable bearing 20 is formed through the cover plate and receives a main drive shaft 21. This drive shaft extends 80 through a bushing 22 and is journaled at its inner end within a bearing 23 formed in the back wall 24 of the gear housing. The outer end of the shaft 21 is fitted with a coupling 25, adapted to be secured to an armature shaft 26 of motor 14 and by which the shaft may be driven.

The back wall 24 of the gear housing is formed with a bearing 27 to receive an anti-friction bearing 28 of a fan shaft 29. This shaft extends horizontally and parallel to the longitudinal axis of the motor. Near the bottom end of the back plate 24 is formed a bearing 30, through which a tubular sleeve 31 extends. This sleeve is provided with an 100 enlarged shoulder at its inner end to prevent it from slipping through the bearing and at the same time is of a suitable bore to accommodate a tubular nozzle shaft 32, at the outer end of which a nozzle or burner tip 33 105 is secured. The nozzle shaft at 32 and the fan shaft 29 are simultaneously driven from the shaft 21 by a gear 34 in mesh with gear 18 previously mentioned, and the gear 35 secured to the shaft 29. Attention is directed to the fact that the ratio of the gears 18 and 35 are at variance with each other,

and that the shaft 29 will run at a higher rate of speed than the shaft 32 for a purpose which will be hereinafter set forth.

Secured against the end wall 24 of the 5 gear housing is a spacing frame 36, against which a plurality of fan housings 37 and 38 are bolted by tie bolts 39. The housing 37 is cylindrical in transverse section, and has a large opening 40 through the wall adjacent to frame 36 and a small opening 41 through the wall adjacent to the housing 38. It is to be understood that any number of 10 the intermediate housings 37 may be used and that it will only be necessary to increase 15 the length of the shaft 29, the shaft 32, and the spacing sleeve 31 in order to change the capacity and vary the performance of the burner. The housing 38 carries a bearing 42 into which the outer end of the fan shaft 20 29 is journaled.

Mounted upon the fan shaft and disposed one within each of the fan housings, are rotors 43. These members consist of circular disks 44 secured to the shaft and carrying 25 a plurality of substantial radial vanes 45. The angle of the blades may be changed if desired, so that they will be tangentially arranged relative to the shaft 29 if desired. These blades are interposed between the 30 disks and the faces of the adjacent housings which are fitted with small openings 41. Thus a multiple stage fan will be produced as the air is drawn in through an intake opening 46, thereafter passing through the 35 first opening 41 and then being forced outwardly to again circulate through an opening 41 and into succeeding housings until emitted through opening 47 in the housing 38. This opening is in communication with 40 an air tube 49 through which the shaft 32 extends, and within the outer end of which the nozzle 33 is disposed. It is to be understood that the outside diameter of the nozzle and the inside diameter of the tube 49 45 bear a definite relation to each other as well as to the speed of rotation of the nozzle and the velocity of the air passing there-around.

The force feed of oil is delivered to the 50 tubular shaft 32 from a suitable supply 50, through a pump 51. This pump is preferably of the gear type, and is driven off of the shaft 21 by a gear 52 in mesh with the gear 53, which gear in turn drives a small 55 gear 54 in mesh with a pump gear 55. It will thus be evident that the pump, the fan and the nozzle may all be driven at different speeds as determined by the conditions required, and as controlled by the 60 change of the various gears of the gear train.

The nozzle is mounted on the outer end of the tubular nozzle shaft 32, and consists of an inner stem 56 suitably secured within the 65 end of the nozzle by screws 57. This stem

has a central oil passage way 58 therethrough, the outer end of the stem terminating a short distance from the end of the oil tube 49. This outer end of the stem is internally threaded to receive a screw 59 70 bearing against a washer 60, by which a cone shaped nozzle tube 61 is secured in position around the end of the stem 56. This tube has a cylindrical portion 62 extending over the stem 56 and resting against a shoulder 75 on a nozzle cup 63. The nozzle cup has an end wall which is interposed between the end of the tubular shaft 32 and the end of the tip, while a cylindrical shell 64 forms a part of the cup and encompasses the cylindrical portion 62 of the tip. The cup and tip are secured in position by the clamping action of the screw 59. The length of the cup is such as to cause its outer vertical lip 80 to extend a slight distance beyond the end 85 of the air delivery tube 49, and to terminate a short distance from the base face 65 of the nozzle tip cone 61. This provides an annular vertical throat 66, into which the oil may flow and from which it passes into the 90 stream of air flowing through the tube 49. The cylindrical shell 64 of the cup 63 is counterbored to form an annular chamber 67 around the base portion 62 of the tip. A shoulder 68 on the tip partially restricts the 95 flow of oil from this annular chamber into the throat 66. In the end wall of the cup a plurality of longitudinally extending passage ways 69 are formed to communicate with the chamber 67. These passage ways 100 also stand in the path of travel of the air flowing through the tube 49 and thus produces a by pass for a portion of the air so that the agitating effect thereof may be utilized in breaking up the oil in the chamber 105 67 and insuring that it will be more thoroughly vaporized when it passes into the main stream of air flowing out from the end of the tube 49. The liquid fuel is delivered from the bore 58 of the stem 56, 110 through radial ducts 70, which extend through the stem and communicate with an intermediate annular recess 71 formed by counterbore in the cylindrical portion of the tip. This portion of the tip is formed with 115 radial ducts 70', preferably in register with the duct 70 of the stem, and through which the liquid fuel may pass to the annular chamber 67.

In view of the fact that different capacities of burner are required, it is often necessary to enlarge the diameter of the air tube 49 and the nozzle. In order that this may be done without impairing the operation of the nozzle, a modified structure is provided as shown in Fig. 3. In this form of the invention, the nozzle tip consists of a conical shell 72 mounted at the end of the tubular shaft 32. Disposed over this shell is a sleeve 73, carrying an inverted cone 130

member 74. The sleeve is perforated as indicated at 75, so that the liquid fuel may pass from the shaft 32 and be carried along the inner face of the inverted cone 74 to the 5 throat 65. The cup 63 is provided with the perforations 69 previously described, and in this instance it will be noted that the outer face of the inverted cone 74 will act to generate the oil so that it will be delivered to a 10 point near the outer periphery of the tip 72.

In operation of the present invention, the burner is assembled as previously described, and after the capacity of the burner has been determined, a nozzle of desired dimension is 15 provided, and the desired number of fan units are assembled to produce the required velocity and volume of air. The gear train may then be designed to establish a desired ratio between the air velocity and the speed 20 of rotation of the nozzle. After the structure has been assembled it may be mounted upon the tripod 10, or permanently installed if desired. In either event, the projecting air tube may extend through an opening 76 25 in a furnace 77, as shown in Fig. 5. It will be observed that in this case the air tube or nozzle may be of such dimensions as to place the motor and fan some distance from the furnace, and that the structure is so assembled as to interpose the fan unit between the furnace and the motor, thus insuring that it will be protected from the extreme heat and will operate in a manner to eliminate repairs.

30 When the motor is set in motion, the fan will be operated as well as the nozzle shaft 32 rotated. It is desirable to design the gear train so that the fan will rotate at a considerably higher rate of speed than the nozzle, and in fact it is desirable to establish 35 this ratio so that the oil delivered through the nozzle will be carried out as a film to the peripheral edge of the nozzle cone base, and that the rotation of the nozzle will not 40 be fast enough to produce a violent action upon the oil and create an excessive and undesirable centrifugal movement thereof. The oil thus delivered to the outer edge of the 45 tip will be of course thrown into the path of travel of the air flowing through the tube 49, and moving at right angles thereto. The 50 force of the moving oil, however, is intended to be arrested by the force of the stream of air so that instead of having a large flaring 55 flame, the air will act to direct the oil particles at right angles to their original path of travel, and will concentrate the flame to 60 produce a flame of relatively small sectional area and of high heat. The congestion of 65 the oil forming a part of the jet thus produced, will be facilitated by the agitation of the oil, and by breaking up the liquid into small globules which will pass from the nozzle tip as of very fine vapor. This result 70 is produced by the mechanical agitation of

the oil within the annular chambers 67 and 71, and by the action of the air which is diverted through the cup 63, and which flows through the passages 69 across the chamber 67, and out around the shoulder 68 75 of the burner tip to the throat 66.

It will thus be seen that by the use of the oil burner here disclosed, it is possible to regulate the formation of the vapor jet produced, and at the same time to insure that 75 the oil therein will be finally vaporized, the burner being further designed to permit it to be carried from place to place and constructed in a manner to meet the requirements of various installations.

80 While I have shown the preferred form of my invention as now known to me, it will be understood that various changes might be made in the combination and arrangement of parts by those skilled in the art, 85 without departing from the spirit of the invention as claimed.

Having thus described my invention, what I claim and desire to secure by Letters Patent, is:

90 1. An oil burner, comprising a tubular, rotatable oil shaft, a fixed air conduit surrounding said shaft, a nozzle disposed in the mouth of said air conduit and carried by the oil shaft, said nozzle being formed with a 95 peripheral outlet passage communicating with the supply of oil in the shaft and adapted to throw by centrifugal action across the path of travel of the air passing around the nozzle and from the end of the 100 conduit, and a plurality of air passageways formed in said nozzle parallel with the longitudinal axis of the shaft and adapted to deliver jets of air into the rear of the peripheral passageway.

105 2. An oil burner, comprising a central rotatable tube through which a supply of oil circulates, a nozzle carried at the outer end of said tube and communicating therewith, said nozzle having a central passageway 110 communicating with the tube, radial passageways emanating therefrom, longitudinal passageways communicating therewith, and a circumferentially extending peripheral outlet adapted to throw oil at right angles to 115 the axes of the nozzle, an air pipe surrounding the oil pipe and a portion of the nozzle, said pipe being of larger diameter than the nozzle and terminating a distance short of the peripheral outlet therefrom, and longitudinal passageways in the nozzle communicating with the air pipe and adapted to deliver a supply of air to the oil passing to the peripheral outlet.

120 3. A burner structure comprising a cylindrical air tube through which air may be delivered under pressure, a cylindrical nozzle member extending into the open discharge end of the air tube, said nozzle having a diameter less than the interior diameter of 130

- the tube whereby an annular space will be formed between the nozzle and the tube, said nozzle being formed with passage ways whereby particles of oil may be thrown off 5 from the nozzle when rotating, and at right angles to the axis of rotation, and means for subjecting the oil to the action of air under pressure prior to and after it has been thrown from the periphery of the nozzle.
- 10 4. A nozzle for oil burners comprising a central tubular member secured to a rotatable shaft through which oil is delivered thereto, said member being formed with a plurality of radial outlet openings, a nozzle cone secured at the end of said tubular member and having a reduced cylindrical body portion whereby a square shoulder will be formed as a part of the base of the cone, said cylindrical body portion being formed with 15 radial openings to receive oil from the first named openings, and a nozzle cup telescoping over said cylindrical body portion and terminating adjacent the base of the cone to form an oil outlet throat, and an annular 20 agitating chamber between the cup and the cylindrical portion of the cone.
5. A nozzle for oil burners comprising a central tubular member secured to a rotatable shaft through which oil is delivered thereto, said member being formed with a plurality of radial outlet openings, a nozzle cone secured at the end of said tubular member and having a reduced cylindrical body portion whereby a square shoulder will be 25 formed as a part of the base of the cone, said cylindrical body portion being formed with 30 radial openings to receive oil from the first named openings, a nozzle cup telescoping over said cylindrical body portion and terminating adjacent the base of the cone to form an oil outlet throat, an annular 35 agitating chamber between the cup and the cylindrical portion of the cone.
6. A nozzle for oil burners comprising a central tubular member secured to a rotatable shaft through which oil is delivered thereto, said member being formed with a plurality of radial outlet openings, a nozzle cone secured at the end of said tubular member and having a reduced cylindrical body portion whereby a square shoulder 40 will be formed as a part of the base of the cone, said cylindrical body portion being formed with radial openings to receive oil from the first named openings, and a nozzle cup telescoping over said cylindrical body portion and terminating adjacent the base of the cone to form an oil outlet throat, an annular 45 agitating chamber between the cup and the cylindrical portion of the cone, and means for creating an agitation of the oil within the annular chamber formed by the cup and prior to the passage of the oil to the outlet throat.
7. A nozzle for oil burners comprising a central tubular member secured to a rotatable shaft through which oil is delivered thereto, said member being formed with a plurality of radial outlet openings, a nozzle cone secured at the end of said tubular member and having a reduced cylindrical body portion whereby a square shoulder 50 will be formed as a part of the base of the cone, said cylindrical body portion being formed with radial openings to receive oil from the first named openings, and a nozzle cup telescoping over said cylindrical body portion and terminating adjacent the base of the cone to form an oil outlet throat, an annular 55 agitating chamber between the cup and the cylindrical portion of the cone, means for creating an agitation of the oil within the annular chamber formed by the cup and prior to the passage of the oil to the outlet throat, and air circulating passageways formed through the end of the cup and adapted to convey air into the annular 60 passage of the cup.

LAURENCE E. FRENCH.
